(57) **CLAIM**

The ornamental design for knitting needle, as shown and described.

DESCRIPTION

FIG. 1 is a front view of a knitting needle;

FIG. 2 is a side view thereof;

FIG. 3 is a top view thereof;

FIG. 4 is a bottom view thereof; and,

FIG. 5 is a cross-sectional view taken along line 5—5 of FIG. 1.

The middle portion is broken away in FIGS. 1 and 2 to indicate that a specific length of knitting needle forms no part of the claimed design.
